UNITED STATES PATENT OFFICE

CLARENCE W. TYDEMAN, OF ENGLEWOOD, COLORADO, ASSIGNOR, BY MESNE ASSIGNMENTS, TO A. OBERHOLTZ, JR., OF DENVER, COLORADO

ABRASIVE REAMER

Application filed July 15, 1929. Serial No. 378,332.

My invention relates to abrasive reamers and is an improvement over my former inventions applied for August 6th 1928 and September 28th 1928, the serial numbers being 297,603 and 308,986 respectively.

In my former inventions there was no quick, positive and reliable method for changing the reamer size beyond the range of its adjustment by the substitution of shoes or blades of a different size.

This made it necessary for a shop to have several different sizes of reamers.

There was also no accurate, delicate and reliable adjustment of the reamer size in fractions of a thousandth part of an inch which the precision of the device warranted in actual service, and the shoes or blades were not supported for their full length, which resulted in slight springing of the shoes or blades when the operator forced the enlarging adjustment too vigorously, resulting in a slightly out of parallel or bell-shaped hole.

The object of my present invention is to provide an abrasive reamer construction in which shoes or blades of widely different diameter or size may be substituted quickly and conveniently, so that but one reamer is required, in which any desired size of blades may be set.

A further object of my present invention is to provide an abrasive reamer construction having a diametral expansion which can be accurately and reliably gauged by a micrometer adjustment to a small fraction of a thousandth part of an inch.

A further object of my invention is to provide an abrasive reamer, the expanding shoes or blades of which are rigidly supported for substantially their entire length so that the reamer will finish a hole exactly parallel even if it is forced or crowded by the workman.

I attain the above objects by providing a construction having two opposed, channeled

shoes or blades adapted to receive sheet abrasive and closely and slidably fitting for their full lengths upon opposite sides of a tapered central body, their position on the body being maintained by a fixed tapered 50 cup keyed and longitudinally movable at the small end of the tapered body, and by a resiliently held floating tapered cup at the large end of the tapered body, and the diameter of the hole reamed being adjusted 55 by the position of the shoes along the tapered body as determined by a micrometer adjustment in which the enlargement of the tapered body per inch of length is properly combined with the threads per inch and the 60 divisions of an adjusting nut on the threaded end of the tapered body, the nut bearing against and longitudinally positioning the solidly held tapered cup against the shoes and the resiliently held tapered cup. 65

All of this is clearly described below and is illustrated in the drawing, in which;—

Figure 1 is an elevation in partial section, of my abrasive reamer.

Figure 2 is an elevation in partial section 70 of Figure 1, taken from above.

Figure 3 is an end view of one of the shoes or blades, as seen from the floating cup end.

Figure 4 is a view of the other end of one 75 of the blades or shoes, that is, as seen from the fixed cup end.

Figure 5 is an end view of the body.

Figure 6 is an end view, in perspective, 80 of one of the sheet abrasives in the position it assumes when mounted on a shoe or blade.

Figure 7 is an enlarged fragmentary section of the body on the line 7—7 of Figure 1, showing a modified section contour, and 85 in dotted lines showing in an exaggerated way the position of a shoe on the body when in operation.

Figure 8 is an enlarged fragmentary section similar to Figure 7 and showing a modi- 90

fied from of contour for the tapered faces 6.

The body 1 is provided with the driving shank 2, which is connected to the mounting shank 3, by the universal connection 4.

5 The body 1 is provided with flat sides 5, and tapered sides 6, providing the large end 7 and the small end 8 of the tapered portion of the body 1.

The extension of the small end 8 is provided with the thread 9 and the keyway 10.

The driving shank 2 has a hole for the reception of the pin 11 which fits in the hollow of the washer 12 and holds it against the pressure of the spring 13.

15 The spring 13 contacts with the floating tapered cup 14 and forces it against the tapered ends 15 of the shoes 16, upon which are mounted the abrasive sheets 17, as will be described below.

20 The tapered contact between the cup 14 and the shoes 16 acts to hold that end of the shoes together and with their tapered faces 18 in contact with the tapers 6 of the body 1.

25 The fixed tapered cup 19 by its contact with the tapered faces 20 of the shoes 16, acts to hold them together and in contact with the tapers 6 of the body 1. The sides 16' of the guide channels of the shoes 16 have a close slidable fit against the flat sides 5 of the body 1. The key 21 of the fixed cup 19 fits in the keyway 10 and is thereby held from turning with respect to the body while permitting longitudinal movement of the cup 19 thereon.

The knurled adjusting nut 22 is in close threaded engagement with the threads 9 of the body 1, and bears against the fixed cup 19, thus positioning the cup 19, the shoes 16 and the cup 14 against the pressure of the spring 13.

40 Adjustment of the nut 22 on the threads 9 adjusts the position of the shoes 16 upon the tapers 6, and thereby adjusts the diameter of the hole reamed by the reamer.

45 When it is desired to replace the shoes with shoes of different size, the floating cup 14 is pushed along the shank 2 against the pressure of the spring 13 till it releases the tapered ends 15 of the shoes, which permits the shoes to be withdrawn from the fixed tapered cup 19. The new shoes are put in place by first inserting their tapered ends 20 in the cup 19, bringing the shoes together till the body 1 fits into their longitudinal channels and their tapered faces 18 contact against the tapers 6 of the body 1, and then permitting the spring 13 to push the floating cup 14 into place where it holds the tapered ends 15 of the shoes together and holds them firmly upon the tapers 6 of the body 1.

50 The sheet abrasives 17 of the size corresponding to the shoes or blades in use, are

55 mounted upon the shoes or blades 16 by being bent to the position shown in Figure 6, and are then slipped upon the shoes endwise, with the mounting edges 24, made of sheet metal or other proper sheet material crimped firmly upon the sheet abrasive 17, slipping in the mounting grooves 25. This holds the abrasive firmly in place on the shoe and in close contact therewith.

60 The outer contour of the shoes or blades 16 is such that when the device is set at its minimum size adjustment with a certain size of shoe, the main contact on the abrasive will be at the sides as at A and A' of Figure 7; and as the setting changes toward the maximum size the main contact will move toward the center of the shoes as at E and E'.

65 In order that the adjusting nut 22 may act as a delicate and accurate micrometer gauge for the diameter of hole finished by the reamer, the following construction is used;

70 The angle of the tapers 6 of the body 1 is such that they separate at the rate of seventy thousandths of an inch (.070") to each axial inch.

75 The threads 9 have twenty eight (28) threads to the inch, so that it takes 28 turns of the nut 22 to enlarge the reamer size seventy thousandths of an inch. Then, one turn of the nut 22 will open the reamer 1/28th of seventy thousandths, or two and one half thousandths of an inch.

80 The cup 19 is provided with the zero mark 27 adjacent its contact with the nut 22, and the nut 22 is divided by the marks 28 into 25 equal divisions.

85 That is, one division is one twenty fifth of a turn for the nut 22, or one twenty fifth of two and a half thousandths, that is, one ten thousandth part of an inch.

90 As the divisions on the nut 22 are roughly an eighth of an inch apart, this permits a careful workman to approximate the proper distance from the nearest division mark and with fair certainty make an adjustment of say one fourth of a division, or one fortieth of a thousandth part of an inch.

95 It is not meant that the ordinary workman can work this close, but this delicate adjustment does provide means whereby a workman can judge how much to turn the nut 22 when making the last finishing touch to a fit, when there is perhaps just a little too much drag as the pin is pushed through the hole.

100 It also permits a workman to finish a hole, note the setting of the nut 22, reduce the size of the reamer by backing off the nut 22 till the reamer will come out of the hole without cutting or scratching, and then on the next hole the known former setting will insure his not adjusting the reamer to a greater size than the preceding hole, if a little care is used, and if he should be careless enough to miss the former setting by an en-

tire division it would mean a variation of but one tenth of a thousandth of an inch in the hole size.

In fitting the pistons and connecting rod ends (when floating pins are used), all of the holes may be roughed out to within a thousandth of an inch of the required size, say, by the aid of this micrometer adjustment, and then the last finishing fit may be 10 easily and quickly made for each individual pin by individual fitting.

In this connection it may be stated that the life of the abrasives is quite surprising.

In one well known make of V-eight automobile engine, the eight pistons and the eight rod ends were rough fit to the same 15 micrometer setting, just to note the amount of wear on the abrasives.

It was found that the greatest variation in 20 size, that is, that between the largest hole of the 16 holes, and the smallest hole, was one half of a thousandth part of an inch. The pins on the same engine were then measured and were found to vary from the largest to the smallest by six tenths of a thousandth part of an inch.

This gives a comparative indication of the 25 extreme accuracy afforded by my reamer with this micrometer adjustment and the full length supports for the shoes.

I am aware that different tapers may be chosen for the body 1, different threads per inch may be employed and a different number of divisions may be marked upon the 35 nut 22, but in any case the result will be the same in that the spread per axial inch of the tapers combined with the number of threads per inch of the adjusting nut give the variations in reamer diameter corresponding to 40 the parts of an inch indicated by the divisions on the adjusting nut.

In Figure 5 it will be seen that when the reamer is turned in the direction indicated by the arrow, the tapered faces 18 of the body 1, are beveled as at 29; that is the lagging corners are beveled.

The reason for this will be more clearly understood by the exaggerated view shown 50 in Figure 7.

In this enlarged view, the rotation as indicated by the arrow D is in the same direction as in Figure 5, but the beveled faces 29 are replaced by the faces 30 of curved contour.

In either case, the main point is that the leading corner of the tapered faces 18 is full, and the lagging corner is relieved.

The contour and the amount of this relief 60 may depend upon several conditions, but the reason for such relief is as follows:

In my experiments with my reamer it was found that if the shoes were very closely fitted upon the body, the reamer worked perfectly, did not chatter nor lock in the hole,

and there was apparently no reason at all to suspect possible trouble.

But, it was also found, that if, in the course of mass production the shoes were fit the least bit too freely upon the body 1, a locking or clutch effect, or a chatter was produced, the clutch effect at times being powerful enough to prevent operation of the reamer.

The explanation is that if, in Figure 7, 75 the body 1 extended to the corner 31 instead of being rounded off to the contour 30, the action would then be as follows:

When the reamer is adjusted till contact with the wall of the hole occurs, say at the point A on the abrasive 17, there is a tendency for the friction thus developed to move the shoe 16 in a direction opposite to the arrow D, with respect to the body 1.

If there is a little play between the body 1 and the shoe 16 this movement between the two will take place about the point 31, say, as a center, and the contact point A will tend to follow the curve B due to the radius R.

In other words the action is that of a clutch which locks the reamer tight in the hole.

If, however, the corner 31 is relieved almost to the corner 32 as shown, the point A will tend to revolve about the corner 32 as a center with the radius R' and will follow the curve C.

The proportions of Figure 7 are much exaggerated, since in actual use the matter concerns at most a few thousandths of an inch, and it is found that the corner 31 need not be relieved more than about half way to the corner 32 under most conditions, but the exaggeration only tends to make what happens more clear.

With the construction shown in Figure 7 the reamer will operate perfectly when revolved in the direction of the arrow D, but will lock tight in the hole when revolved in the opposite direction.

The diameter of the hole being reamed, the thickness and the width of the body 1, and the outer contour of the shoes 16 are all of them factors which combine to determine what amount of the lagging corners of the tapered faces of the body 1 should be removed, or how close to their leading corners the faces 18 should be relieved. This matter of proportion can be readily determined by trial by any intelligent mechanic, once he is aware that the lagging corner must be relieved enough to prevent the lock action mentioned, or to prevent chattering.

If it is desired to build a reamer that can be revolved in either direction, then both corners of the taper faces 18 must be considered lagging corners, since one will be lagging when the reamer is revolved in one direction, and the other will be lagging

when the reamer is revolved in the other direction.

In this case, with both corners relieved, the tapered faces 18 will be reduced to little more than a line midway between the two corners.

This is illustrated in Figure 8, in which the similar contours 33 intersect on the tapered face 18 in the center of the body 1.

10 Since this construction from a practical standpoint is slightly more difficult to make, and since there is no particular advantage in a reamer that may be revolved in either direction, I prefer the construction shown in 15 Figures 5 and 7, though any mechanic will appreciate that the construction best suited from all standpoints to the particular case in hand, should of course be employed.

20 The following may be stated as further explanation of the reason for the relief of the body 1 as at 29 or 30;

If there is any play between the shoe and the body it has been found by actual test that the instrument will chatter or lock unless 25 the lagging corners of the faces 18 are relieved. It can be seen that when the tension is applied and the reamer is snug in the hole the shoe will tend to hang back and twist or cock with respect to the body until the 30 sides 16' of the shoe guide channels touch the body sides 5 and the faces 18 of the shoes touch the sides 6 of the body.

If the play between shoes and body is such as to permit enough of this twisting 35 or cocking movement between them, the clutch effect mentioned above is produced.

My reamer is not necessarily limited to a two blade or shoe construction, since any other number of blades may be employed if 40 desired, so long as they are supported for substantially their entire length and are adjusted by a proper micrometer adjustment. So, I do not mean to confine the construction narrowly to a two blade or shoe construction.

45 Actual tests, however, have shown that a two shoe or blade reamer is just as efficient as one having more shoes or blades and it is of course cheaper to manufacture.

Having now described my invention, what 50 I claim as new, and desire to protect by Letters Patent, is as follows;—

1. In an adjustable abrasive hole-finishing cutting tool, a central body having parallel sides joined by tapered faces forming a 55 tapered portion having a small and a large end and provided with a threaded portion extending from the said small end and a driving shank extending from the large end, a mounting shank, means forming a universal connection between the mounting shank and the driving shank, a cup on said driving shank facing said large end, resilient means longitudinally positioning the cup against the said large end, shoes provided with 60 abrasive members fitting upon said body and

radially positioned by said tapered faces and at the said large end adapted to extend into said cup and be thereby held upon said body, a cup on said threaded portion and adapted to receive the end of the shoes at the small end of the said tapered portion and thereby hold the shoes on the body, and an adjusting screw threadedly engaging said threaded portion and adapted to bear against the adjacent cup and to position the shoes against the pressure of said resilient means.

2. In a cutting tool having a central body with tapered faces and shoes provided with abrasive members fitting thereon, cups fitting over the ends of said shoes and thereby holding them upon the said body, a spring positioned upon the said body and bearing against one of said cups, and an adjusting member threadedly engaging said body and adapted to bear against the other cup.

3. In a cutting tool having a central body with faces tapered a predetermined part of an inch per axial inch, and shoes provided with abrasive members fitting thereon and contacting said tapered faces for substantially their entire length, cups fitting the ends of said shoes and thereby holding the shoes in place on said body, a spring positioned upon the said body and bearing against one of said cups to hold it against the shoes, an adjusting member threadedly engaging the said body by a predetermined number of threads per inch and in contact with the other cup and adapted to position it and the shoes against the pressure of the first cup and said spring, the adjusting member and adjacent cup acting as micrometer members, one of which carries an index mark and the other of which is provided with a plurality of marks equally spaced to combine with the taper of said tapered faces, and the threads per inch of said engagement between the body and the adjusting member to indicate a predetermined part of an inch per division of movement of one of said micrometer parts with respect to the other.

4. In a cutting tool, a central body with tapered faces and shoes provided with abrasive members fitting thereon and having contact with said tapered faces for substantially the entire length of said shoes, cups fitting the ends of said shoes and adapted to thereby hold them upon said body, a spring upon the said body bearing at one end against one of said cups, means upon the said body to position the other end of the spring, and an adjusting member threadedly engaging said body and adapted to bear against and axially position the other cup, and adjust the diameter of said tool by change of the axial position of said shoes upon said body against the pressure of said spring.

5. In a cutting tool having a threaded central body with tapered faces and shoes provided with abrasive members fitting thereon,

- cups fitting the end of said shoes and thereby holding them upon the said body, a spring positioned upon the said body and bearing against one of said cups, the other 5 cup having a guided axially movable engagement with said body and an adjusting member in threaded engagement with the threads of said body and bearing against the guided cup, the cup and the adjusting member 10 acting as micrometer members one of which carries an index mark and the other of which is provided with a plurality of equally spaced division marks, whereby the movement of the adjusting member one of 15 said divisions combined with the pitch of said threads and the angle of said tapered faces will move the shoes axially on said body and thereby vary their diameter a predetermined part of an inch.
- 20 6. In a cutting tool having a threaded central body with tapered faces and shoes provided with abrasive members fitting thereon and having contact with said tapered faces for substantially the entire length of said 25 shoes, cones fitting the ends of the said shoes and adapted to thereby hold them upon said body, a spring carried by the body and bearing against one of said cones, the other cone having a guided axially movable engagement 30 with said body and acting as a micrometer part, and an adjusting member threadedly engaging said body and bearing against the guided cone and acting as another micrometer part, one of said parts provided with an index mark, and the other part 35 provided with a scale of equal divisions, whereby the movement of said adjusting member one division will axially move the shoes and vary the tool diameter by a predetermined part of an inch.
- 40 7. In a cutting tool having a central body with tapered faces, abrasive-supporting shoes internally tapered to fit said tapered faces of the body, two cups on the body in 45 contact with the ends of said shoes and holding them upon said body, a spring supported on said body and bearing against one of said cups, and means on said body positioning the other cup against the pressure of 50 said spring.
- 55 8. In a cutting tool having a central body with two opposed faces joined by two substantially parallel faces and having abrasive-supporting shoes fitting thereon, cups internally tapered and fitting over the ends 60 of said shoes mounted upon said body and thereby holding the shoes on the body, and a spring positioned upon said body and bearing against one of said cups to hold it in 65 resilient contact with the adjacent ends of the said shoes.
- 70 9. In a cutting tool having a central body with tapered faces and having an abrasive-supporting, bevel-ended shoe fitting upon each tapered face, two internally tapered 75 cups on said body in contact with the ends of said shoes, a spring support on said body adjacent one of said cups, a spring between said support and the adjacent cup, and means positioning the other cup on the body 80 against the pressure of said spring.
10. A hone or abrading tool comprising a shank threaded at one end and having a shank body rectangular in cross section with tapered side walls, a pair of shoes adjustably mounted on the shank body and having inner inclined faces tapered reversely to the tapered faces of the shank body, a nut threaded on said threaded end of the shank, an enlarged annular collar confining the 85 lower ends of the shoes adjustable by said nut, a collar slidable on the upper end of the shank having an enlarged annular flange confining the upper ends of the shoes, a coil spring on the shank engaging the collar, 90 means on the upper end of the shank engaging the spring to place the same under tension and hold the collar engaged with the shoes, an abrading sheet inclosing the shoes, and means for retaining the sheet on the 95 shank.
11. A cutting or abrading tool comprising a body member of substantially rectangular cross section, two substantially identical abrasive supporting shoes, each shoe having a rectangular guide channel extending longitudinally thereof, said guide channels being of the proper size to receive the edges of the body member, the body member serving as a means for rotating the shoes about its longitudinal axis, the lagging corners of the body members being chamfered, and means for holding the shoes in place on the body member. 100
12. A cutting or abrading tool comprising a body member having a substantially rectangular body portion whose edges are 105 equally inclined with respect to its longitudinal axis of symmetry, two substantially identical abrasive supporting shoes, each shoe having a rectangular guide channel whose bottom is inclined with respect to the outer surface of the shoe at the same angle as the sides of the body member with respect to its axis of symmetry, the body member 110 serving as means for rotating the assembly, the lagging corners of the body member being chamfered and means for holding the 115 shoes and body member in assembled relation.
13. In a cutting tool having a central body with tapered faces, each provided with a beveled edge, abrasive-supporting shoes internally tapered to fit said tapered faces and two cups on the body in contact with the ends of the shoes and holding them upon said body, the cups being movable in the direction of the length of the body to position the shoes for the purpose of adjustment and for holding them in adjusted position. 120
- 125

14. In a cutting tool having a central body with tapered faces, each face having a beveled edge, abrasive supporting shoes fitting upon said faces, means for holding the shoes in position on the body member and means for adjusting the position of the shoes in the direction of the length of the tapered face to adjust the diameter of the tool and for holding the shoes in adjusted position.
- 5 10 In testimony whereof I affix my signature.
